INKED RIBBON

Jacob A. L. Möller, Rye, N. Y., assignor to Manifold Supplies Company, Brooklyn, N. Y., a corporation of New York

Application April 30, 1947, Serial No. 744,849

11 Claims. (Cl. 197—172)

1

The present invention relates to improved inked ribbons, and, more particularly, to improved ribbons for typewriter machines, billing machines and the like, and improved processes of producing the same.

Heretofore, it has been well known that a great variety of inked ribbons have been proposed and some actually have been used. Of the prior ribbons, those of a silk type possessed certain advantages but also had certain shortcomings and disadvantages. Various attempts were made to overcome the shortcomings and disadvantages, but none of such attempts was wholly satisfactory and successful especially when carried into practice on an industrial scale for the production of commercial articles.

It has been discovered that the shortcomings and disadvantages of the prior inked ribbons can be avoided and that a novel ribbon can be produced which will satisfy the requirements of the art.

The invention likewise contemplates the provision of an inked ribbon, particularly of the silk type, which can be manufactured with machinery on an industrial scale for production of a commercial article.

Moreover, the invention provides a typewriter ribbon, particularly of the silk type, which has a practical and usable thinness which has a skip weave with a silk face and a cotton back and which still possesses a substantial reservoir of ink.

Furthermore, it is also within the contemplation of the invention to provide a unique typewriter ribbon having a novel combination of elements and features.

Another object of the invention is the provision of an improved inked ribbon possessing a working face having smoothness and "sheen," possessing substantial uniformity throughout its length, and possessing increased strength over prior ribbons.

Other objects and advantages will become apparent from the following description taken in conjunction with the accompanying drawings, in which:

Fig. 1 is a reproduction of a photomicrograph taken at 20 magnifications of a portion of the improved inked ribbon illustrating the novel combination of elements and features embodying the present invention; and

Fig. 2 is a similar view taken at 40 magnifications.

Referring to the drawings and more particu-

larly to Fig. 2, the reference character W designates the warp threads and the reference character F the filler or weft threads. In practice it has been discovered that novel results can be obtained by utilizing a mixture of nylon threads and silk threads for the warp threads and long, staple cotton yarn for the weft threads. I have found that the skip weave must be used for best results. By a skip weave I mean one in which the 5 warp or weft threads or filaments skip two or more of the other threads or filaments. From comprehensive tests, it has been discovered that the silk threads and nylon threads are preferably disposed across the face of the typewriter 10 type and softer, slightly coarser and moderately spaced cotton threads are run up and down with the type, thus giving a finer and smoother writing surface. As a result of the discovery, it was found that the novel construction embodying the 15 present invention was especially adapted to conform to the configuration of the typewriter type. Thus, the face of typewriter type being greater in height than in width, it was found essential to arrange the weave to have numerous fibers or fine 20 yarns running across the face from right to left in order to reduce as much as possible the undesirable "fabric marks" in the printed type on the paper. Generally speaking, type such as used 25 on a typewriter consists of one or two or usually 30 at most three perpendicular portions or lines with comparatively short lines or curves. By utilizing the improved weave embodying the present invention in a typewriter ribbon, the finest possible 35 and greatest number of yarns are provided across the perpendicular parts of the type characters and softer, slightly coarser and moderately spaced 40 cotton threads or yarns are disposed up and down with the perpendicular parts of the type. In practice, the silk threads and nylon threads are 45 used for the warp yarns and the cotton as the weft or filling yarns. In conducting research on typewriter ribbons and the like of the character described herein, it was further discovered that the nylon threads must be woven in the ribbon at least two in every nine threads. As those skilled in the art know, the cloth is woven as wide 50 as forty (40) inches and must be slit into ribbons after weaving. When a typewriter ribbon and the like is manufactured to embody the present invention, it has been found that such a ribbon has good ink-carrying capacity with increased strength over prior ribbons of the plain or skip weave, possesses greater ink-carrying capacity than a silk ribbon, discharges ink more completely.

ly than plain silk, retains its edge better without ravelling than prior ribbons made wholly or mainly of synthetic fibers such as nylon, possesses longer life, and gives better service in use. In practice, it has been found that best results are obtained when nylon varies broadly from about 10% to about 15% by weight of the entire ribbon, silk varies from about 38% to about 48% by weight and cotton from about 39% to about 49% by weight, and preferably from about 12% to about 14½% of nylon, about 40% to about 45% of silk and about 39% to about 45% cotton. The best commercial product made on an industrial scale contains about 13½% nylon, about 43½% silk, and about 43% cotton.

The manufacture of the ribbons can be conducted in any appropriate manner. However, in making up the silk yarn, it is preferred to take raw silk from a plurality of bales in order to blend it and then subject the proper number of filaments to a very light twist in making up the warp yarn. It has been discovered that it is essential to oil the silk warps before weaving. Such oiling is preferably done at a temperature of about 100° F. after which the surplus oil is removed in a spinning basket. The silk is first impregnated with the oil and then subsequently the excess oil is eliminated from the basket by spinning or rotating it. As a result of experiment, it has been found preferable to use such oils as olive oil, cocoanut oil and the like. Other oils such as neat's-foot oil, and sulphonated oils and the like may be used.

In weaving the web of material, a sufficient number of silk warp yarns are then beamed. This is preferably effected in a manner well known to those skilled in the art. The loom on which the web is woven is not the plain "over and under" type, but it is arranged so that the harness of the loom lifts and drops the warp yarn at irregular but pre-determined intervals—staggered to produce a web of fabric that has most of the silk on the face and most of the cotton in the back without loss of firmness. In connection with the weft yarn, a high grade, lightly twisted, long-staple cotton is used which is obtained on cops from which it is wound on to the spool which goes into the bobbin of the loom, as those skilled in the art will readily understand. In practice, it is preferred to make up the warp using at least two nylon threads in every nine warp threads, the remainder of which are pure silk. The threads of nylon should have about the same thickness as the silk threads. This arrangement of nine is repeated across the entire width of the fabric. The arrangement of the warp to produce the smoothest possible surface while still maintaining sufficient "firmness" in the woven fabric, is to have each warp thread, which forms the smooth surface, pass under one weft thread and then over four, repeating this arrangement throughout the length of the piece with every set of four warp yarns or threads. The warp thread next to it follows the same scheme of under one and over four but the arrangement is staggered so that no two adjacent warp threads follow the same identical course over and under the weft threads. In so doing, a new type of ribbon is produced having the most desirable combination of unusual strength, resiliency, and super-smoothness of surface.

After weaving the web of fabric, it is essential to have it finished. It has been found that satisfactory results can be obtained by eliminating the outer layer of ceresin from the silk. In

carrying this operation to practice, it has been found that great care must be taken not to over-boil nor to underboil. In underboiling an objectionable stiff ceresin layer would be left surrounding the core of pure silk partially or wholly which would reduce the ink absorbency of the fabric, and in overboiling the raw silk would be attacked and would be weakened. The foregoing finishing operations are rather delicate and must be conducted with the greatest of care.

After the finishing operation, the web of fabric is put through a calender stack which is heated, and the web of fabric is steamed to dampen it. In this manner, it is practical to iron out the web flat and smooth. After the calendering operation, or before as well, if preferred, the web of fabric is very carefully singed on both sides to burn off any projecting ends of fiber, particularly the ends of cotton, and especially those that might protrude beyond the face of the fabric. Under certain circumstances, it is preferred to singe the web of fabric both before and after the calendering operation.

The web of fabric can now be slit and edged in a ribbon machine to produce "satinized ribbon." After slitting and edging, the satinized ribbon can be inked in the conventional manner. Upon completion of the inking operation, the inked ribbon is cut to lengths and is then rolled on the usual typewriter reels and the like.

It is to be observed that the present invention provides a novel inked ribbon, such as a typewriter ribbon, which possesses advantages over prior ribbons and which is not to be confused with the plain skip weave ribbon which is disclosed in U. S. Patent No. 1,830,620 which was granted to George E. Pelton.

Although the present invention has been described in conjunction with preferred embodiments, it is to be understood that modifications and variations may be resorted to without departing from the spirit of the invention, as those skilled in the art will readily understand. Thus, instead of using a cut edge on the ribbon, a woven edge may be used. Similarly, in place of nylon threads, other equivalent threads having similar properties, such as vinyl plastic threads sold under the name Vinyon, may be used.

I claim:

50 1. As an improved article of manufacture, a typewriter ribbon and the like having a silk face and a cotton back and comprising an inked woven fabric made of a staggered weave having at least two nylon threads in every nine warp

55 threads, the remainder being silk and having the weft threads composed of cotton, thereby providing better conformation to the configuration of type, greater reduction of undesirable fabric marks, greater ink-carrying capacity, greater strength, greater discharge of ink, and greater edge retention without raveling than prior ribbons.

60 2. As an improved article of manufacture, a typewriter ribbon and the like having a silk face and a cotton back and comprising an inked woven fabric made of a staggered weave having at least two nylon threads in every nine warp threads, the remainder being pure silk substantially devoid of ceresin and having the weft threads composed of lightly twisted, long staple cotton, thereby providing better conformation to the configuration of type, greater reduction of undesirable fabric marks, greater ink-carrying capacity, greater strength, greater discharge of

70 75

ink, and greater edge retention without raveling than prior ribbons.

3. As an improved article of manufacture, a typewriter ribbon and the like having a silk face and a cotton back and comprising an inked woven fabric made of a staggered weave having at least two nylon threads in every nine warp threads, the remainder being silk and having the weft threads composed of cotton, each warp thread passing under one weft thread and then over four, thereby providing better conformation to the configuration of type, greater reduction of undesirable fabric marks, greater ink-carrying capacity, greater strength, greater discharge of ink, and greater edge retention without raveling than prior ribbons.

4. As an improved article of manufacture, a typewriter ribbon and the like having a silk face and a cotton back and comprising an inked woven fabric made of a staggered weave having at least two nylon threads in every nine warp threads, the remainder being silk and having the weft threads composed of cotton, said nylon constituting from about 10% to about 15% by weight of the ribbon, said silk constituting from about 38% to about 48%, and said cotton constituting from about 39% to about 49%, thereby providing better conformation to the configuration of type, greater reduction of undesirable fabric marks, greater ink-carrying capacity, greater strength, greater discharge of ink, and greater edge retention without raveling than prior ribbons.

5. As an improved article of manufacture, a typewriter ribbon and the like having a silk face and a cotton back and comprising an inked woven fabric made of a staggered weave having at least two nylon threads in every nine warp threads, the remainder being silk and having the weft threads composed of cotton, said nylon constituting from about 12% to about 14½% by weight of the ribbon, said silk constituting from about 40% to about 45%, and said cotton constituting from about 39% to about 45%, thereby providing better conformation to the configuration of type, greater reduction of undesirable fabric marks, greater ink-carrying capacity, greater strength, greater discharge of ink, and greater edge retention without raveling than prior ribbons.

6. As an improved article of manufacture, a typewriter ribbon and the like having a silk face and a cotton back and comprising an inked woven fabric made of a staggered weave having at least two nylon threads in every nine warp threads, the remainder being silk and having the weft threads composed of cotton, said nylon constituting from about 13½% by weight of the ribbon, said silk constituting about 43½%, and said cotton constituting about 43%, thereby providing better conformation to the configuration of type, greater reduction of undesirable fabric marks, greater ink-carrying capacity, greater strength, greater discharge of ink, and greater edge retention without raveling than prior ribbons.

7. In the manufacture of an improved typewriter ribbon and the like having a staggered weave, that improvement which comprises blending raw silk from a plurality of bales, subjecting a selected number of silk filaments to a very light twist in making up the warp yarn, treating the silk warps with oil, weaving a web of fabric with cotton wefts and said silk warps

supplemented with nylon warps, to produce a staggered weave, finishing the web of fabric including eliminating the outer layer of ceresin from the silk without overboiling or underboiling, calendering the thus-finished web of fabric to iron out the same flat and smooth, slitting the calendered web into ribbons, edging the slit ribbons, and inking the edged ribbons for use in the typewriter and the like, whereby an improved ribbon is produced having a silk face and a cotton back and having better conformation to the configuration of type, greater reduction of undesirable fabric marks, greater ink-carrying capacity, greater strength, greater discharge of ink, and greater edge retention without raveling than prior ribbons.

8. In the manufacture of an improved typewriter ribbon and the like having a staggered weave, that improvement which comprises blending raw silk from a plurality of bales, subjecting a selected number of silk filaments to a very light twist in making up the warp yarn, treating the silk warps with oil, weaving a web of fabric with cotton wefts and said silk warps supplemented with nylon warps, to produce a staggered weave, said nylon constituting from about 10% to about 15% by weight of the ribbon, said silk constituting from about 38% to about 48%, and said cotton constituting from about 39% to about 49%, finishing the web of fabric including eliminating the outer layer of ceresin from the silk without overboiling or underboiling, calendering the thus-finished web of fabric to iron out the same flat and smooth, slitting the calendered web into ribbons, edging the slit ribbons, and inking the edged ribbons for use in the typewriter and the like, whereby an improved ribbon is produced having a silk face and a cotton back and having better conformation to the configuration of type, greater reduction of undesirable fabric marks, greater ink-carrying capacity, greater strength, greater discharge of ink, and greater edge retention without raveling than prior ribbons.

9. In the manufacture of an improved typewriter ribbon and the like having a staggered weave, that improvement which comprises blending raw silk from a plurality of bales, subjecting a selected number of silk filaments to a very light twist in making up the warp yarn, treating the silk fibres with oil, weaving a web of fabric with cotton wefts and said silk warps supplemented with nylon warps, to produce a staggered weave, said nylon constituting from about 12% to about 14½% by weight of the ribbon, said silk constituting from about 40% to about 45%, and said cotton constituting from about 39% to about 45%, finishing the web of fabric including eliminating the outer layer of ceresin from the silk without overboiling or underboiling, calendering the thus-finished web of fabric to iron out the same flat and smooth, slitting the calendered web into ribbons, edging the slit ribbons, and inking the edged ribbons for use in the typewriter and the like, whereby an improved ribbon is produced having a silk face and a cotton back and having better conformation to the configuration of type, greater reduction of undesirable fabric marks, greater ink-carrying capacity, greater strength, greater discharge of ink, and greater edge retention without raveling than prior ribbons.

10. In the manufacture of an improved typewriter ribbon and the like having a staggered

weave, that improvement which comprises blending raw silk from a plurality of bales, subjecting a selected number of silk filaments to a very light twist in making up the warp yarn, treating the silk fibres with oil, weaving a web of fabric with cotton wefts and said silk warps supplemented with nylon warps, to produce a staggered weave, said nylon constituting about 13½% by weight of the ribbon, said silk constituting about 43½%, and said cotton constituting about 43%, finishing the web of fabric including eliminating the outer layer of ceresin from the silk without overboiling or underboiling, calendering the thus-finished web of fabric to iron out the same flat and smooth, slitting the calendered web into ribbons, edging the slit ribbon, and inking the edged ribbons for use in the typewriter and the like, whereby an improved ribbon is produced having a silk face and a cotton back and having better conformation to the configuration of type, greater reduction of undesirable fabric marks, greater ink-carrying capacity, greater strength, greater discharge of ink, and greater edge retention without raveling than prior ribbons.

11. In the manufacture of an improved typewriter ribbon and the like having a staggered weave, that improvement which comprises blending raw silk from a plurality of bales, subjecting a selected number of silk filaments to a very light twist in making up the warp yarn, treating the silk warps with oil, weaving a web of fab-

ric with cotton wefts and said silk warps supplemented with nylon warps to produce a staggered weave, each warp thread passing under one weft thread and then over four, finishing the web of fabric including eliminating the outer layer of ceresin from the silk without overboiling or underboiling, calendering the thus-finished web of fabric to iron out the same flat and smooth, slitting the calendered web into ribbons, 5 edging the slit ribbons, and inking the edged ribbons for use in the typewriter and the like, whereby an improved ribbon is produced having a silk face and a cotton back and having better conformation to the configuration of type, 10 greater reduction of undesirable fabric marks, greater ink-carrying capacity, greater strength, greater discharge of ink, and greater edge retention without raveling than prior ribbons.
